WHEEL COVER

Frederic P. Plotkin, 1044 Hiltz Ave., Los Angeles, Calif.

Filed Dec. 24, 1958, Ser. No. 53,893

Term of patent 14 years

(Cl. D14—30)

Fig. 1 is a front view of a wheel cover, showing my new design, the ridged decorative pattern being continuous as indicated by the broken lines; and

Fig. 2 is a cross-section taken along the line of 2—2 of Fig. 1.

Fig. 3 is a cross-section taken along the line of 3—3 of Fig. 2.

Fig. 4 is a perspective view of the wheel cover shown in Fig. 1.

The broken lines in Fig. 2 partially show a conventional wheel and tire for illustrative purposes only.

I claim:

The ornamental design for a wheel cover, substantially as shown and described.
